Primary Examiner — Mark Goodwin(74) *Attorney, Agent, or Firm* — NSIP Law(57) **CLAIM**

The ornamental design for a handle for home appliance, as shown and described.

DESCRIPTION

FIG. 1 is a perspective view of a handle for home appliance, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof; and,

FIG. 9 is a perspective view of a handle for home appliance of FIG. 1, in which a gas-range oven in broken lines is provided to illustrate an example environment.

The broken lines are for illustrative purposes only and form no part of the claimed design. The shade lines in the figures show contour and not surface ornamentation.
